CLAIM

The ornamental design for a carrying case for glucose monitors as shown and described.

DESCRIPTION

FIG. 1 is a front view of the carrying case for glucose monitors;

FIG. 2 is a bottom view of the carrying case for glucose monitors of FIG. 1 thereof;

FIG. 3 is a left side view of the carrying case for glucose monitors of FIG. 1 thereof;

FIG. 4 is a right side view of the carrying case for glucose monitors of FIG. 1 thereof; and,

FIG. 5 is a front view of the carrying case for glucose monitors of FIG. 1 thereof with a glucose monitor device contained inside the case;

Broken lines in FIG. 5 show a glucose monitor which illustrates environment of the carrying case for glucose monitors that forms no part of the claimed design. The remaining broken lines show stitching that does not form part of the claimed design.

1 Claim, 5 Drawing Sheets
